UNITED STATES PATENT OFFICE.

FREDERICK S. KEYES, OF WARREN, MASSACHUSETTS.

WAVE-MOTOR.

No. 798,348.

Specification of Letters Patent.

Patented Aug. 29, 1905.

Application filed August 31, 1904. Serial No. 222,839.

To all whom it may concern:

Be it known that I, FREDERICK S. KEYES, a citizen of the United States, and a resident of Warren, in the county of Worcester and State of Massachusetts, have invented a new and Improved Wave-Motor, of which the following is a full, clear, and exact description.

My invention relates to apparatus for utilizing the energy of such movements in large bodies of water as waves. Its principal objects are to provide an apparatus of this character in which the intermittent movement will be transformed into a continuous force by integrating the energy of successive waves and different parts of the same wave.

Reference is to be had to the accompanying drawings, forming a part of this specification, in which similar characters of reference indicate corresponding parts in all the figures.

Figure 1 is a top plan view of one embodiment of my invention. Fig. 2 is a side elevation of one of the piers and its approach. Fig. 3 is a broken vertical sectional detail through one of the conduits and a portion of the pier. Fig. 4 is a top plan view illustrating one of the transmitting mechanisms, parts being broken away and in section. Fig. 5 is a horizontal section through one of the conduits and a portion of those adjacent to it, taken in a plane above the float. Fig. 6 is a transverse vertical section in a plane between two of the transmitting-wheels. Fig. 7 is a detail in elevation of the gate-controlling mechanism; and Fig. 8 is a view similar to Fig. 1, illustrating another embodiment of my invention.

The letters P P designate piers or structures, which are shown as arranged in a continuous series situated along a shore-line L. The preferable location for these piers will be that at which to the seaward there is a deep offing unbroken by rocks or islands and having a sandy bottom of easy slope near the shore. Such conditions avoid the breaking up of the waves into short or irregular forms and enable the piers to be readily constructed of considerable length. Each pier may include a foundation 10, carried for a suitable distance below the sea bottom and being formed of concrete or other convenient material. Upon each foundation is erected the superstructure which is to contain and support the motor mechanisms, this consisting of side walls 11, to be constructed of sheet iron or steel, and which are arranged in triangular or V shape with the apex toward the

direction of advance of the waves and with the inclined sides diverging shorewardly. The walls are shown as bolted to the foundation by anchors 12 and may be braced in any desired manner by stays 13. Stability may be imparted to the piers by filling each structure with water, which may be admitted by a gate 14, preferably located with its lower edge substantially at the low-tide line, it being shown as near the apex of the pier. The top of the structure is covered by a suitable floor 15, upon which the various transmitting and power-receiving mechanisms may be situated, and this floor, as illustrated, is connected with the shore by an approach 16, supported upon a skeleton structure 17, which permits the water to move laterally after its entrance and distribute itself uniformly for retreat seaward. The piers are situated adjacent to one another, their sides making substantially equal angles with the shore and converging to open throats at 19 to allow the passage of the unspent portions of the waves.

Along the outer or inclined sides of each pier are situated series of substantially vertical casings or conduits 20, which are preferably rectangular in horizontal section and are formed between partitions 21, with their fronts closed by a continuous wall 22. To secure greater strength, this outer wall is preferably double, the inner and outer sections being connected by braces 23. These external walls, at least in regard to the surfaces which are subjected to the action of the waves, are plane or substantially smooth, and in them at the bottom are mouths 24 into the conduits. The mouths are extended vertically sufficiently to give an opening of greater area than that of the conduits in transverse section, insuring the entrance of water amply sufficient to supply the conduits; yet this vertical extension does not diminish the number of conduits which may be arranged in a series. As illustrated in Fig. 2, the position of these conduit mouths is such that they are at all times below the trough of the wave, even at low tide, thus preventing the access of surface water, which carries with it destructive floating matter. This arrangement, moreover, diminishes the shocks to which the conduits are subjected, the wave action causing a continuous column of water to be moved up and down therein. The bottom of each conduit from the mouth is preferably inclined inwardly and upwardly at 23^a, where it merges into a curved or concave portion 24^a, giving an enlargement extending

above the mouth and to the rear of each conduit. As is particularly shown in Fig. 2, the inclination of the portions 23^a is at different angles at different portions of the pier, this angle gradually increasing from a horizontal plane toward the shore. The outflow of the water over this steeper decline tends to wash away and prevent the accumulation of sand where the bottom most closely approaches the 10 conduit-mouths.

Associated with each conduit is a motor mechanism, which may comprise a cylindrical float 25, preferably constructed of sheet metal and having a conical or pointed lower end 26 and a convex or curved upper end 27. This float is shown as weighted at 28 to the desired extent, and from the weight a stay 29 projects vertically to a plate 30, secured on the inner side of the head of the float. Fixed to the outer side thereof above this plate is a chamber 31, the upper end of which may be closed by a cover-plate 31^a. Extending vertically along the sides of each conduit are ways, conveniently formed by angle-bars 32, between which operate pairs of guides 33. As the length of the outer way is greater than that opposite, which is limited by the curvature of the conduit enlargement, the lower guide 34, operating upon its inner way, may be extended to preserve the coaction in the lowermost position of the float. In the chamber 31 is situated a head 35, from which rises a motor-bar 36. This head is preferably cushioned by springs 37, located above and below it, and which to a great extent absorb the shocks to which the float is subjected and relieve the strains upon the rack and motor mechanism. Each bar 36, as illustrated, extends along an upright 38, moving between guides 39. Extreme movements of the float under extraordinary impulses should be limited and the concussion cushioned. Upon its upward travel this is effected by a buffer-plate 40, movable beneath the floor and guided by rods 41, while between it and the floor is situated a spiral spring 42, holding it normally downward. With this buffer-plate the top of the chamber 31 may contact, compressing it and lessening the abruptness of the concussion. Upon its downward movement the shock may be taken up by a projection 43, fixed near the upper extremity of the bar and coöperating with a similar cushion or buffer device 44, mounted upon a convenient beam 46.

Secured to or formed upon each bar 36 is a rack 47, communicating the movement of the float to transmitting mechanism M. This mechanism preferably comprises a pinion 48, meshing with the rack and fixed upon a shaft 49, journaled in standards 50. Upon a hub of this pinion are formed ratchet-teeth 51, coacting with similar teeth 52 upon the hub of a pinion 53, the teeth being forced into engagement by a spring 54. This spring may 65 at one end contact with the standard and at

the other with a plate 55, held against lateral movement by arms 56, projecting from the standard and operating against a washer 57, interposed between it and the pinion 53. The ratchet-teeth are so arranged that when the float is rising under the impulse of the crest of the wave the teeth slip by one another and no rotation of the pinion 53 results; but when the float is falling with the trough of the wave the teeth engage and the weight of the float rotates the pinion, thus securing a more uniform action than would be imparted by the varying wave motion. Meshing with the pinion 53 is a gear 58, formed upon a transmission-wheel 59, mounted to turn loosely upon a suitably-journalized shaft 59^a, there being, if desired, a bushing 59^b interposed between the wheel and shaft. To limit the movement of this wheel to one direction or that which is caused by the falling of the float, it is preferably provided with ratchet-teeth 60, with which coact a suitable number of pawls 60^a, here illustrated as pivoted upon the beam 46.

In the face of the wheel opposite the ratchet-teeth is shown a plurality of curved channels, conveniently three in number and concentrically arranged, each extending through nearly three hundred and sixty degrees, but having at least a slight space separating their adjacent ends. One end of each channel at 61 may open outwardly at full width, while from this for the remainder of its length extends a reduced opening or slot 62. In each channel operates a spring 63, preferably extending when not under compression for substantially its full length, and contacting with the end of each spring adjacent to the opening 62 is a stud 64, having an enlarged head 65, which may be introduced through the opening and then follow the spring along the channel, its shank moving through the slot. The studs 64 are fixed upon the adjacent face of a wheel 66, mounted in the same manner about the shaft 59^a, as is the wheel 59. In the opposite side of the wheel 66 are channels similar to those just described, in which are springs coacting with studs upon a second wheel 66, these being continued in a series of any desired extent, depending upon the amount of spring-compression which it is desired to secure. The last of the series of transmission-wheels has its springs engaged by studs upon a fly-wheel 67, keyed to the shaft to rotate therewith.

At one extremity of the shaft 59^a, Fig. 1, is fixed a cone-pulley 68, connected by a belt 69 with a similar pulley 70, carried by a power-receiving shaft 71. The cone-pulleys furnish one form of speed-controlling mechanism, and to automatically operate this a governor 71^a of any convenient type may be driven from the shaft 71 by suitable gearing 71^b and be connected by a lever 71^c with a belt-shifter 71^d, serving to move the belt 69 over the cone-

pulleys, and thus maintain the speed of the power-receiving shaft substantially constant. Mounted upon the shaft 71 are pulleys 72, which are shown as having clutches 73, by which they may be rotatably connected with the shaft or disengaged therefrom. These pulleys are joined by suitable belts or other gearing with power-receiving mechanism, which, as illustrated, consists of electric generators 74, there being a number of suitable units upon each of the shafts 71, so that the effect of comparatively small wave movement may be utilized. At their outer ends the power-receiving shafts of each pier are shown as connected by clutches 75 with gearing 76 to a shaft 77, extending longitudinally of the pier and across its approach to a shaft 78, to which the shaft 77 of each pier is connected by gearing 79. Geared to this last-named shaft is a power-receiving mechanism or generator 80. By adding the effects of the motor mechanisms of a plurality of piers and applying them to one or more suitable units wave motions so small as to be ineffective through the motor mechanism of a single pier may be satisfactorily utilized to generate power.

In Fig. 8 is illustrated another arrangement of power-receiving mechanism. Here the shafts 59^a upon each pier are connected at their inner ends by gearing 81 with a transverse shaft 82. Each of the shafts 82 carries a pulley 83, with a clutch 84 associated with it, and these pulleys may be connected by wire rope or other gearing 85 with pulleys 86, which are connected by transmitting mechanisms M, similar to those employed in connection with each of the motor mechanisms, with a main power-receiving shaft 87. This shaft may in turn be connected with generators 88, through cone-pulleys and speed-controlling mechanism S, such as has been previously described. In this manner a series of piers of any feasible magnitude may exert their aggregate effect upon one or more power-receiving mechanisms in accordance with the energy which is being generated by the waves at any particular time.

Between the outer double walls of the conduits and at each side of said conduits are mounted vertical ways, conveniently formed by angle-bars 89, serving to guide gates 90, operating across the conduit-mouths to control the extent of their opening. These gates may be braced by suitable members 91 to resist the pressure exerted by the water against them. From each gate rises an operating-rod 92, which has extending from it above the floor of the pier a rack 93, with which meshes a pinion 94. Each pinion preferably carries upon its hub the member 95 of a jaw-clutch, with which co-operates the companion member 96, splined for longitudinal movement upon and rotation with a shaft 97, extending along the edge of the pier. Connected with the member 96 of each clutch is an

operating-lever 98, fulcrumed at 99 upon any convenient support and having attached to it, above and below the fulcrum, flexible members 100 100, which may pass over guide-rolls 101 to a lever 102, the levers of the entire series preferably being located at the apex of the pier, the movement of any lever in one direction or the other serving to bring its clutch into engagement or to release it. The shaft 97 is shown as connected by suitable gearing 103, which is preferably so proportioned as to increase the power of the moving force, to a shaft upon which is fixed a pulley 104, operated by a belt 105 from some convenient source of power. In the operation of the system it may be desirable—as, for example, when the waves are running high—to partially close all the gates, and this may be simultaneously effected for an entire series by throwing each of the clutches into engagement by its lever and then rotating the shaft 97 in the proper direction. If, on the other hand, but one or a portion of the gates are to be moved, this may be accomplished with equal readiness by bringing into coaction the clutches of the gates which are to be operated. As the weight of each gate and its rod would tend to close it when its clutch is out of engagement, I prefer to provide locking mechanism 95 which may consist of a toothed hub or annular projection 106, carried by each of the pinions 94, having coacting with it a pawl 107, which is connected by an operating member 108 with the upper extremity of the clutch-lever 98. The relation of the elements is such that the effect of the initial movement of the lever to bring the clutch members together will first raise the pawl and when the engagement of the clutch is completed fully release the teeth 106 from the pawl and allow the movement of the gate. The reverse of the lever throws in the pawl upon the separation of the clutch members. The tendency of the gates to close may be diminished and the readiness of operation increased by suitable counterweight devices 109. As the waves encounter the apices of the piers they are smoothly divided thereby without breaking the sea and producing short cross-waves, which tend to cause abrupt movements of the motor mechanism. Each wave as it travels above the conduit-mouths will compel the column of water contained therein to rise as the crest approaches and to fall with the trough. The height of each wave is preserved substantially constant for its entire movement between the piers by the fact that their inclination is in proportion to the amount of water taken up by the conduits—that is, the passage grows gradually narrower as the area of conduit-mouths increases. As each float rises the ratchet mechanism connecting its rack with the transmitting-wheels will slip over; but as the float falls under the effect of its constant weight the 130

ratchet-wheels engage and through the intermediate pinion and gear rotate the first of the transmitting-wheels. This movement presses the ends of its springs against the studs of the 5 next wheel, compressing them, and if it be sufficient communicates movement to the next wheel and so on throughout the series. If, however, the effect of one wave is not sufficient to accomplish this, as the float again 10 rises the movement of the first wheel will be controlled and be prevented from backing off and losing the energy which has been stored in its springs by the pawls 60°. Then the following impulse of the float will further 15 press the springs until the effect has become sufficient to rotate the entire series together with the fly-wheel. Thus the force is built up, the springs expanding during each succeeding rise of the float to communicate to the 20 shaft 59^a the energy which is stored in them. Each of the transmitting mechanisms acts in the same manner, and their aggregate effect is applied to the shaft to produce a steady and substantially uniform rotation, an averaging 25 of the wave height being obtained by the fact that the floats of each series are being acted upon by all parts of one or more waves, as is indicated in Fig. 2. Furthermore, all the fly-wheels will act in unison to receive a momentary excess of energy from any of the floats. 30 The energy thus applied to the transmitting-shafts is communicated to the power-receiving shafts and then to suitable receiving mechanisms located either upon the piers or 35 upon the shore and of such capacity as may be necessary to meet the existing conditions. As the waves pass beyond the last conduit they enter the contracted throats between the piers and expand or distribute themselves laterally beneath the approach without choking the inlets or tending to break the regularity of succeeding waves. In the case of a violent 40 wave motion, such as would be produced by storms, the gates may, if necessary, be almost entirely closed to throttle the force and prevent its exerting an undue effect; but if the movement is such that the float reaches its extreme positions it will be arrested by 45 the cushions, so that no destructive shocks will result. At the same time the spring connection between the float and its bar assists in this cushioning and takes up the impact of 50 lesser wave movements.

It will be noted that as the water enters 55 each conduit it will be directed first upwardly by the inclined bottom and the horizontal movement gradually changed to the vertical by the curvature of the wall of the enlargement. This curvature also directs 60 the inflowing water against the opposite side of the float from that which receives the pressure at the upper edge of the mouth and tends to balance it. Water passing the float in the conduit is free to drain itself in the 65 open corners formed between the cylinder

and rectangular walls, the curvature of the top of the float facilitating this. In addition the cylindrical form of the float gives the least lateral hold upon its submerged surface by a swirling column of water, minimizing 70 the friction on the ways and guides. The rectangular form of the conduit also tends to reduce the lateral friction and thrust by lessening the swirl. The angular lower end enables it to enter the water in its downward 75 movement without unnecessary concussion and leave it without excessive suction, this being also reduced by the unobstructed passage of the water through the open corner spaces. 80

It should be further noted that as the mouths of the conduits are always below even the troughs of the waves at low tide such floating matter as timbers, which would be liable to destroy the parts by their impact 85 or seaweed and smaller stuff which would tend to clog, will be excluded.

Having thus described my invention, I claim as new and desire to secure by Letters Patent—

1. A wave-motor comprising a series of 90 conduits adapted to be successively acted upon by a wave, and a motor mechanism associated with each conduit.

2. A wave-motor comprising a series of conduits, a motor mechanism associated with 95 each conduit adapted to be successively acted upon by a wave, and means for connecting the motor mechanisms.

3. A wave-motor comprising a series of conduits, a motor mechanism associated with 100 each conduit, and means for cushioning the movement of the motor mechanism.

4. A wave-motor comprising a series of conduits, a motor mechanism associated with each conduit, and means for storing the energy imparted to each motor mechanism and simultaneously cushioning its application. 105

5. A wave-motor system comprising a series of conduits arranged in a position inclined to the general line of advance of the 110 waves, and motor mechanism associated with the conduits.

6. A wave-motor system comprising a series of substantially vertical conduits arranged in a position inclined to the general 115 line of advance of the waves, and motor mechanism associated with the conduits.

7. A wave-motor system comprising a plurality of series of conduits diverging from the direction of advance of the waves, and motor 120 mechanism associated with the conduits.

8. A wave-motor system comprising a plurality of series of conduits diverging from an apex against which the waves are projected, and motor mechanism associated with the conduits. 125

9. A wave-motor system comprising a plurality of series of conduits converging toward one another, and motor mechanism associated with the conduits. 130

10. A wave-motor system comprising a plurality of series of conduits converging to an open throat, and motor mechanism associated with the conduits. 70
- 5 11. A wave-motor system comprising a series of conduits arranged in a position inclined to the general line of advance of the waves, a motor mechanism associated with each conduit, and means for connecting the motor mechanisms. 75
- 10 12. A wave-motor system comprising a series of conduits arranged in a position inclined to the general line of advance of the waves, a motor mechanism associated with each conduit, and means for cushioning the movement of the motor mechanisms. 80
- 15 13. A wave-motor system comprising a series of conduits arranged in a position inclined to the general line of advance of the waves, a motor mechanism associated with the conduits, and means for storing the energy imparted to the motor mechanism. 85
- 20 14. The combination with a V-shaped pier, of a series of conduits arranged along the inclined sides of the pier, and motor mechanism associated with the conduits. 90
- 25 15. The combination with a plurality of V-shaped piers situated with the ends of their inclined sides adjacent to one another, of conduits arranged along said inclined sides, and motor mechanism associated with the conduits. 95
- 30 16. The combination with a plurality of V-shaped piers situated with the ends of their inclined sides adjacent to but separated from one another, of conduits arranged along said inclined sides, and motor mechanism associated with the conduits. 100
- 35 17. The combination with a pier situated offshore and having continuous outer walls in which are openings, of conduits extending from the openings, motor mechanism associated with the conduits, and a skeleton structure connecting the pier and shore. 105
- 40 18. A wave-motor comprising a conduit, a weighted float movable in the conduit, power-receiving mechanism, means for transmitting the movement of the float to the power-receiving mechanism when the former is acted upon by gravity, and means for cushioning said movement. 110
- 45 19. A wave-motor comprising a conduit, a float movable in the conduit, power-receiving mechanism, and means for storing energy prior to the movement of the power-receiving mechanism interposed between the float and power-receiving mechanism. 115
- 50 20. A wave-motor comprising a conduit, a float movable in the conduit, power-receiving mechanism, and a spring interposed between and serving to transmit the movement of the float to the power-receiving mechanism. 120
- 55 21. A wave-motor comprising a conduit, a float movable in the conduit, power-receiving mechanism, a spring, and means for controlling the direction of expansion of the spring. 125
- 60 22. A wave-motor comprising a conduit, a float movable in the conduit, power-receiving mechanism, a spring, and ratchet mechanism for controlling the direction of expansion of the spring. 70
- 65 23. A wave-motor comprising a conduit, a float movable in the conduit, and independently-rotatable ratchet members for transmitting the movement of the float in one direction. 75
- 70 24. A wave-motor comprising a conduit, a float movable in the conduit, and a plurality of ratchet mechanisms for transmitting the movement of the float in one direction and preventing reverse movement. 80
- 75 25. A wave-motor comprising a conduit, a float movable in the conduit, ratchet mechanism for transmitting the movement of the float in one direction, power-receiving mechanism, a spring interposed between the power-receiving mechanism and ratchet mechanism, and ratchet mechanism for controlling the movement of the spring. 85
- 80 26. A wave-motor comprising a member movable by the waves, a shaft, a fly-wheel fixed upon the shaft, a transmitting-wheel movable about the shaft, and a spring co-operating with the fly-wheel and transmitting-wheel. 90
- 85 27. A wave-motor comprising a member movable by the waves, a shaft, a fly-wheel fixed upon the shaft, a transmitting-wheel movable about the shaft, a spring carried by one of the wheels, and a projection upon the other wheel contacting with the spring. 95
- 90 28. A wave-motor comprising a member movable by the waves, a shaft, a fly-wheel fixed upon the shaft, a transmitting-wheel movable about the shaft and provided with a curved channel, a spring situated within the channel, and a projection upon the fly-wheel extending into the channel and contacting with the spring. 100
- 95 29. A wave-motor comprising a member movable by the waves, a shaft, a fly-wheel fixed upon the shaft, a transmitting-wheel movable about the shaft and provided with a plurality of curved channels, springs situated within the channels, and projections upon the fly-wheel extending into the channels and contacting with the springs. 105
- 100 30. A wave-motor comprising a member movable by the waves, a shaft, a fly-wheel fixed upon the shaft, a plurality of transmitting-wheels movable about the shaft, and springs co-operating with adjacent wheels. 110
- 105 31. A wave-motor comprising a member movable by the waves, a shaft, a fly-wheel fixed upon the shaft, a series of transmitting-wheels movable about the shaft and each provided with a plurality of curved channels, springs situated within the channels, and projections from the adjacent wheels extending into the channels and contacting with the springs. 115
- 110 32. A wave-motor comprising a member 120
- 115
- 120
- 125
- 130

movable by the waves, a shaft, a fly-wheel fixed upon the shaft, a transmitting - wheel movable about the shaft, a spring coöperating with the fly-wheel and transmitting-wheel, 5 and ratchet mechanism associated with the transmitting-wheel.

33. A wave-motor comprising a rectangular conduit, a cylindrical float movable in the conduit, and transmitting mechanism connected 10 with the float.

34. A wave-motor comprising a conduit, a float movable in the conduit and having a pointed lower end and a convex upper end, and transmitting mechanism connected with 15 the float.

35. A wave-motor comprising a rectangular conduit provided with ways, a cylindrical float movable in the conduit, guides fixed to the float and coöperating with the ways, and transmitting mechanism connected with the float. 20

36. A wave-motor comprising a conduit, a float movable in the conduit, a rack extending upwardly from the float, gearing meshing with the rack, power-receiving mechanism, 25 and ratchet mechanism interposed between said gearing and power-receiving mechanism.

37. A wave-motor comprising a conduit, a float movable in the conduit and having a chamber, a head movable within the chamber, and a 30 spring contacting with the head.

38. A wave-motor comprising a conduit, a float movable in the conduit and having a chamber, a head movable within the chamber, and a spring contacting with each side of the 35 head.

39. A wave-motor comprising a conduit, a float movable in the conduit, transmitting mechanism connected with the float, and a cushion situated near the upper end of the 40 conduit and with which the float may contact.

40. A wave-motor comprising a conduit, a float movable in the conduit, a rack extending upwardly from the float, gearing meshing with the rack, a projection from the rack, and a 45 cushion with which the projection may contact.

41. A wave-motor comprising a series of substantially vertical conduits having mouths and walls adjacent to the mouths and inclined 50 at different angles, a float movable in the conduit, and transmitting mechanism connected with the float.

42. A wave-motor comprising a series of substantially vertical conduits having mouths and walls adjacent to the mouths and inclined 55 at gradually-varying angles, a float movable in the conduit, and transmitting mechanism connected with the float.

43. A wave-motor comprising a conduit 60 having a mouth and a curved enlargement situated opposite said mouth, a float movable in the conduit, and transmitting mechanism connected with the float.

44. A wave-motor comprising a conduit 65 having a mouth and a curved enlargement sit-

uated opposite said mouth, there being an inclined wall leading from the mouth to the enlargement, a float movable in the conduit, and transmitting mechanism connected with the float. 70

45. A wave-motor comprising a conduit having a mouth, a float situated in the conduit, a gate coöperating with the conduit-mouth, and means for positively moving the gate in both directions. 75

46. A wave-motor comprising a plurality of conduits each having a mouth, a float situated in each conduit, a gate coöperating with each conduit - mouth, means for simultaneously moving the gates toward and from said conduit-mouth, and means for connecting and disconnecting each gate with reference to the moving means. 80

47. A wave-motor comprising a conduit having a mouth, a float situated in the conduit, 85 a gate coöperating with the conduit-mouth, and means for locking the gate in place.

48. A wave-motor comprising a conduit having a mouth, a float situated in the conduit, 90 a gate coöperating with the conduit-mouth, and a counterweight for the gate.

49. A wave-motor comprising a plurality of conduits each having a mouth, gates coöperating with the conduit-mouths, racks extending from the gates, a shaft situated adjacent 95 to the racks, pinions loosely mounted upon the shaft and meshing with the rack, clutches for securing the pinions to the shafts, a float operating in each conduit, and transmitting mechanism connected with the floats. 100

50. A wave-motor comprising a plurality of conduits each having a mouth, gates coöperating with the conduit-mouths, racks extending from the gates, a shaft situated adjacent to the racks, pinions loosely mounted upon the shaft 105 and meshing with the rack, clutches for securing the pinions to the shaft, a float operating in each conduit, transmitting mechanism connected with the floats, and means for simultaneously operating the clutches. 110

51. In a wave-motor system, the combination with a foundation, of an inclosing structure, means for admitting water to the enclosure, conduits situated along a side of the enclosure, and motor mechanism associated with 115 the conduits.

52. In a wave-motor system, the combination with a structure, of conduits arranged along a side of the structure and having double outer walls, braces between the walls, and motor mechanism associated with the conduits. 120

53. In a wave-motor system, the combination with a structure, of conduits arranged along a side of the structure and each having 125 a mouth and a double outer wall, motor mechanism associated with the conduits, and gates for closing the conduit-mouths operating between the walls.

54. The combination with a plurality of 130

wave-motors, of a transmitting-shaft, a power-shaft, and means for connecting said shafts, and automatic means operating upon the connecting means for controlling the rotation of the power-shaft.

55. The combination with a plurality of wave-motors, of a transmitting-shaft, a power-shaft driven thereby, cone-pulleys upon the shafts, a belt connecting the pulleys, and automatic means for moving the belt.

56. The combination with a plurality of wave-motors, of a transmitting-shaft, a power-shaft driven thereby, cone-pulleys upon the shafts, a belt connecting the pulleys, and automatic means for moving the belt controlled by the rotation of the power-shaft.

57. A wave-motor system comprising a plurality of separate piers, each provided with a series of motor mechanisms, power mechanism associated with each pier, and means for connecting the power mechanisms between the piers.

58. A wave-motor system comprising a plurality of separate piers, each provided with a series of motor mechanisms, power mechanism associated with each pier, power-receiving

mechanism common to all the piers, and means for storing the energy imparted by each pier to said common power-receiving mechanism.

59. A wave-motor system comprising a plurality of separate piers, each provided with a series of motor mechanisms, power mechanism associated with each pier, power-receiving mechanism common to all the piers, and means for storing the energy imparted by each pier to said common power-receiving mechanism and simultaneously cushioning its application.

60. A wave-motor comprising a plurality of conduits each having a mouth, a float situated in each conduit, a gate coöperating with each conduit-mouth, means for simultaneously moving the gates, and means for independently connecting each gate with the moving means.

In testimony whereof I have signed my name to this specification in the presence of two subscribing witnesses.

FREDERICK S. KEYES.
